UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

PROCESS OF DRILLING HOLES.

1,290,172.

Specification of Letters Patent. Patented Jan. 7, 1919.

Application filed October 5, 1915. Serial No. 54,252.

To all whom it may concern:

Be it known that I, GEORGE H. GILMAN, a citizen of the United States, and a resident of Claremont, county of Sullivan, and State of New Hampshire, have invented an Improvement in Processes of Drilling Holes, of which the following description, in connection with the accompanying drawings, is a specification, like characters on the drawings representing like parts.

My invention relates to processes of drilling holes in minerals, and more particularly though not exclusively to processes of drilling holes in rock.

There have come into general use three great generic classes of drills for drilling rock. Of these the oldest is probably the rotary drill which was subsequently modified into the core drill. The core drill uses a drill bit having a relatively large hole, the bit being pressed against the rock and rotated, thereby cutting an annular channel in the rock about a core protected by the surrounding bit. The cutting by rotary action alone is relatively slow, and this method of drilling holes is rarely used in connection with power drills except where it is desired to preserve the core.

The second great method of drilling holes in extensive use, is the reciprocatory drilling system, which is essentially percussive. A solid drill steel or one having a relatively small hole for the introduction of cleansing fluid is used, which steel is reciprocated to strike a series of percussive blows on the rock to be drilled, usually with rotation of the steel between but not during the blows. A modification of this system uses a drill bit having a large hole therein so that an annular channel is cut. This is done, not to save the core, but to drill a hole of relatively large diameter while abrading a relatively small amount of rock. Several disadvantages accompany this method. The drill, relying on impact owing to its momentum does not cut as fast when lightened, and the withdrawal of the drill steel from the end of the hole between the blows permits pieces of the core (which generally is somewhat shattered) to fall in front of the bit and prevent the securing of the maximum efficiency thereof for subsequent cutting.

The third method of drilling, commonly called the hammer drill method, uses a bit either solid or with a relatively small hole 55 therein, which is held loosely in the path of a reciprocating power hammer element, rotation usually being given to the drill steel between successive blows of the hammer element. This method, while very successful, 60 has several disadvantages. Practically all the rock in the hole has to be abraded, and when the hole is in a considerable distance, the blow of the hammer is, to a large extent, 65 absorbed by the anvil effect of the long and relatively heavy drill steel. There is also a tendency to side spring which, when a certain depth is passed, absorbs much of the blow imparted by the hammer. An improvement which has recently come into extensive use comprises the use of a pressure fluid feed to press the drill against the work; but, although this greatly increases the efficiency of the drill by eliminating, to some extent, the personal equation, hammer 70 drills are used generally only for drilling holes of relatively small diameter and to relatively small depths.

By my improved method I am enabled to drill a hole of the usual small diameter much 80 faster, and with much less expenditure of power. I am also enabled to save a core, if I so desire. I am enabled to drill holes of much larger diameter in proportion to the size of drilling engine used, also saving a 85 core, if so desired. I can also largely overcome the usual disadvantages attending the drilling of holes of relatively great depth, by to a large extent reducing the inertia or anvil effect of the drill and also the side 90 spring thereof.

I may accomplish the above by a process of drilling holes which comprises cutting an annular channel around a core of rock by combined percussive and rotary action of a 95 non-reciprocatory core surrounding element, and removing the core, thereby cutting a relatively large hole by abrading a relatively small amount of rock. The bit, having a relatively large hole axially therein, is relatively light in proportion to its diameter; thus what is a disadvantage in a reciprocatory core drill becomes an advantage in the hammer core drill, for in the former the

reciprocating steel should have weight to increase the impact, while in the latter weight should be avoided to increase the impact.

It is also well understood that a tube is the strongest structure into which a given amount of metal can be formed to withstand bending strain or side spring in all directions. Thus in proportion to the cross sectional area of my drill bit, and hence in proportion to the amount of stone to be abraded, my process provides a means of avoiding, to a large extent, the absorption of the impact by side spring of the steel.

I preferably press my drill steel toward the work by a constant pressure during the drilling operation. Thus the steel is firmly pressed against the work so that there is substantially no rebound thereof following the blows thereon, and also the pressure is available during the rotary action of the drill bit to abrade somewhat the material being cut, even between the blows of the hammer drilling engine.

It will be noted that by my process the core may be constantly surrounded and supported throughout its entire length by the drill steel. Thus even if the core becomes cracked, as is usually the case, it will remain in its proper position within the drill steel.

My process is adapted to be used in drilling holes in any direction, but is peculiarly well adapted for drilling holes horizontally at an upward angle to the horizontal or at a slightly downward angle to the horizontal, for in drilling holes in these directions practically the whole core usually comes out within the drill bit, for seams in the rock or the shaking of the bit usually cause a crack across the core adjacent the end of the bit.

To prevent friction and, if desired, to introduce water or air and water to wash away the material abraded, I may construct my hollow cutting member with a slightly restricted opening adjacent the cutting edges, so that the core, except at and adjacent the cutting point of the bit, is loosely held in the hollow of the drill steel so that it may crack into sections, and so that, if desired, the water or air or a mixture of the two may pass around the core to the point of the bit and cause the abraded material to leave the hole by passing back along the exterior of the drill steel, which is preferably somewhat enlarged in diameter at the cutting point.

While my process may be performed with any suitable apparatus, I have illustrated

herewith an apparatus well adapted to perform my process when properly handled by a skilled operator.

In the drawings of this illustrative apparatus:—Figure 1 is a sectional view, partly in elevation, of a pressure fluid fed, rotative hammer drilling engine having connections for feeding air or water or both to the drill steel.

Fig. 2 is an enlarged side elevation, partly in section, of the point of a bit adapted to be used in connection with my process.

Fig. 3 is an enlarged end elevation of the point of the drill bit illustrated in Fig. 2.

Fig. 4 is a sectional elevation on the line 4—4 of Fig. 3.

As the construction and operation of drilling engines is well known to those skilled in the art, and as my present invention pertains to processes of drilling and not to details of construction other than the generic types of construction referred to in describing my process, I make no detailed description of the apparatus illustrated.

While I have described rather specifically the process of drilling, and have illustrated a drilling apparatus well adapted to perform my process, I do not limit myself to the process described. The scope of my invention can be best determined by the appended claims.

Claims—

1. That process of drilling relatively large holes in rock which comprises cutting an annular channel around a core by alternate percussive and rotary abrasive action of a cutting element produced by alternately percussing and rotating said element, said element being held against the rock during its rotation with a sufficient pressure to exert an abrasive action on said rock.

2. That process of drilling relatively large holes in rock which comprises cutting an annular channel around a core by alternately percussing and rotating a cutting element while holding said element in engagement with the rock and preserving said core substantially intact.

In testimony whereof, I have signed my name to this specification, in the presence of two subscribing witnesses.

GEORGE H. GILMAN.
